UNITED STATES PATENT OFFICE.

GEORGE T. BUCHANAN, OF HIGHLAND PARK, MICHIGAN.

TELEGRAPH TRANSMITTING INSTRUMENT.

1,152,287.

Specification of Letters Patent. Patented Aug. 31, 1915.

Application filed August 27, 1914. Serial No. 858,791.

To all whom it may concern:

Be it known that I, GEORGE T. BUCHANAN, a citizen of the United States, residing at Highland Park, in the county of Wayne 5 and State of Michigan, have invented new and useful Improvements in Telegraph Transmitting Instruments, of which the following is a specification.

This invention relates to telegraph instruments and particularly to transmitters therefor, and has for its object to provide a simple instrument of this kind that may be operated by any person whether familiar with or ignorant of telegraphy and the 10 Morse alphabet, to send a message correctly over the line by the simple act of depressing in succession finger keys that represent letters and numerals, which keys will, when pressed down, each automatically cause the 15 instrument to transmit over the line in Morse characters the letter or numeral indicated thereon.

The invention comprises a sending key similar to the well-known Morse key combined with a series of key levers operable by the fingers, each lever representing a letter or numeral and having on one end projections or teeth of different lengths separated by spaces and arranged in such combinations that when brought into engagement with the telegraph key by depressing the finger keys the former will be operated to send over the line the characters of the Morse alphabet, or equivalent code signals 25 that represent the letters on the operated finger keys. To prevent duplication of the letters on the return movement of the key levers, means are provided to bring the key levers and telegraph key into coöperation 30 only during the depression of said finger keys, and to cause their separation before the finger keys are permitted to rise or return to their normal position.

In the accompanying drawings, Figure 1 45 is a plan view of the improved transmitter. Fig. 2 is a side elevation of the same. Fig. 3 is a front elevation. Fig. 4 is a side view enlarged of the trip device for causing the coöperation and separation of the telegraph 50 key with the finger key levers. Fig. 5 is a plan view of the same parts. Fig. 6 is a perspective view of the operating end of one of the finger key levers.

In the drawings, 10 indicates a base upon 55 which various parts of the instrument are mounted, and may be made of wood or other

insulating material. Screwed to the upper side of the base at the center thereof and extending transversely across the same are two guides 11 spaced a suitable distance apart 60 and placed parallel to each other. Between the guides and sliding longitudinally therein is a plate 12 from the rear end of which rise two vertical standards 13 to a suitable height, said standards being joined at their 65 upper ends by cross-connections 14. Projecting forwardly from the top of each standard 13 is a bearing 15 in each of which is mounted a pivot screw 16 said screws forming the fulcrum of a rocking 70 lever 17 of cruciform shape, the horizontal arms of which have depressions in their ends to form seats for the pointed ends of the pivot screws 16. The rocking lever 17 is with one exception similar to the lever 75 of an ordinary Morse key in that it has a back-stop 19 and a front stop 20, the latter being held away from a contact point 21 on the lower cross-bar 14 and insulated therefrom, by a spring 22. The lower free 80 end of the lever 17 instead of having the usual insulated handle of the Morse key, has connected thereto a horizontal rod 23 that extends across the instrument from side to side for a purpose to be hereinafter 85 described. The contact point 21 is connected as shown to a binding post 24 while the frame of the instrument is electrically connected to a binding post 25, to these binding posts the wires of the telegraph line 90 are connected.

The telegraph key just described mounted on the uprights 13 and plate 12 have a short movement in the guides 11, said movement being limited by a stop 26 fastened to the 95 base 10 at the rear of the plate, and a like stop 27 in front of the plate.

At a suitable distance in front of the telegraph key is a horizontal shaft 28 mounted at its ends in bearings 29 fixed to the base 100 10 at each side thereof. Journaled on the shaft are a plurality of finger key levers 30, their forward ends being provided with buttons or finger keys 31, each of which is provided with a letter or numeral. On the rear 105 of each key lever 30 is a T-head 32 preferably curved, the center of curvature being the axis of the pivotal point of the levers 30. From the rear edge of the head 32 project teeth 33, some of which are longer than 110 others and separated by spaces, said teeth being combined to form letters or numerals

of the Morse alphabet corresponding to the letters and numerals on the finger keys at the opposite ends of the key levers 30. A spring 35 fixed to the base and bearing at its free end against the underside of each lever serves to maintain the forward operating ends of said levers in elevated position, and the teeth or projections 33 on the opposite end below the plane of the rod 23 on the telegraph key. Depression of the keys by the fingers raises the heads 32 and the teeth or projections 33 thereon engage the rod 23 and actuate the telegraph key, the short teeth forming the dots and the long teeth the dashes of the Morse alphabet.

The plate 12 supporting the telegraph key is normally held in its rearmost position against the stop 26 by a spring 36, and in this position the rod 23 is behind the range of movement of the teeth 33 when the keys are depressed. To bring the rod 23 into position to coact with the teeth 33 when the levers 30 are depressed and move away therefrom before their return movement to prevent a repetition of the signal, means are provided to be actuated by the levers 30 when depressed to automatically draw the plate 12 and the parts mounted thereon in a forward direction, and at the completion of said depression disengage said plate and permit it to return under the influence of the spring 36 whereby the rod 23 is moved backward and beyond the teeth 33 of the returning levers 30. This means comprises a short horizontal shaft 37 extending across the plate 12 and mounted at its ends in bearings 38 fastened to the base 10 or to the guides 11 as shown. Fast on the shaft 37 are two arms 39 that project in a forward direction and carry a horizontal rod 40 that lies just below the bottom edges of the levers 30, the rod being of such length as to extend beneath all of said key levers, and upon the depression of any of said levers the rod 40 is lowered and rocks the shaft 37. An arm 41 fixed on the shaft 37 extends in a rearward direction for a short distance and then turns upward, the vertical portion of said arm having a slot 42 therethrough from front to rear through which extends the hooked end 44 of a link 43, the opposite end of which link passes through a slot in the upright 13. The hooked end of the link 43 is held in engagement with the arm 41 by a spring 45 connected to said link and to the upright 13, said spring also forms a yielding connection between the link and the upright. The underside of the hook is beveled upwardly in a forward direction as at 46 to engage a trip pin 47 mounted in projections 48 on the bearings 38.

The operation of the instrument as thus constructed is as follows: When a finger key 31 is depressed to raise the head 32 and projections thereon, the rod 40 is depressed by

the downward movement of said key levers and rocks the shaft 37, swinging the arm 41 in a forward direction and through the connection of the hooked end of the link 43 with said arm draws the plate 12 and the telegraph key supported thereby in a forward direction so that the rod 23 on the lower end of said telegraph key will be in position to be actuated by the teeth 33 as they rise. After the teeth have passed the rod 23 and just before the completion of the depressing movement of the key lever 30, the hook 44 on the link 43 will be disconnected from the rod 41 on the shaft 37 by the inclined surface 46 of the hook 44 riding over the stop pin 47, which lifts said hook sufficiently to permit it to slide freely through the slot 42 in the arm 41 when the plate 12 is drawn rearwardly by the spring 36. The rod 23 by this movement is carried rearwardly of the teeth 33, so that when the key 31 is released the spring 35 returns the lever 30 to its normal position and the teeth 33 move downwardly without encountering the rod 23.

What I claim as new is,—

1. A telegraph instrument comprising a Morse key, the operating lever thereof having a horizontal rod affixed to its free end, a plurality of finger key levers each representing a different letter or character, projections or teeth on one end of each lever adapted to coöperate when depressed with said rod to actuate the Morse key, means actuated by each of said key levers when depressed to cause said Morse key to move into engagement with said teeth or projections, and a trip for disconnecting said means to permit the return of the Morse key before the key lever rises.

2. In combination with a plurality of key levers each having on one end projections or teeth, a swinging circuit-closing lever having a rod on its free end adapted to be engaged by the teeth on each key lever when depressed to send a signal over the line, a sliding support on which said circuit-closing lever is mounted, means actuated by the key levers when depressed to move said support and carry the circuit-closing lever into engagement with the projections on the downwardly moving key lever, and releasing means to permit the return of said support and said key when the depression movement of the key lever is completed.

3. In combination with a plurality of key levers each having on one end projections or teeth, a swinging circuit closing lever adapted to be engaged by the projections on each key lever when depressed to send a signal over the line, a sliding support for said circuit closing lever, resilient means for holding said sliding support and the circuit closing lever away from the key levers, a rocking member below the key levers actu-

ated upon the depression of each key lever to move the sliding support toward the key levers, and a trip connection between said member and said support that is released before the return of the key lever and permits the return of the support.

4. In combination with a plurality of key levers each having on one end projections or teeth, a swinging circuit closing lever adapted to be engaged by the projections on each key lever when depressed to send a signal over the line, a sliding support for said circuit closing lever, resilient means for holding said support and the circuit closing lever away from the projections, a rocking member below the key levers actuated upon the depression of each key lever to move the circuit-closing lever into engagement with the key lever, a link connected at one end to the sliding support and having a hook on its opposite end to engage the rocking member for the purpose of moving said circuit-closing lever into position for cooperation with said projection, and tripping means for releasing the hooked end of said connecting link to permit the return movement of the sliding support.

5. A telegraph instrument comprising a Morse key, a plurality of finger key levers each provided with means on one end for operating the Morse key, a rocking member below the key levers adapted to be actuated upon the depression of each lever, a link connection between the Morse key and to the rocking member for moving said Morse key when the key levers are depressed into cooperative relation therewith, a spring for drawing the Morse key away from the key levers, and tripping means between said link

and the rocking member to permit the Morse key to return under tension of said spring.

6. A telegraph instrument comprising a Morse key, a sliding support on which said Morse key is mounted, a plurality of finger key levers having projections or teeth on one end representing a different letter or character and adapted to coöperate with and actuate the Morse key when said key lever is operated, means actuated by the operation of each key lever to move said sliding support and bring said Morse key into engagement with said teeth or projections, said sliding support and key lever being returned to normal position upon the complete operation of said key lever.

7. In combination with a plurality of key levers each having on one end projections or teeth, a sliding support, a swinging circuit-closing lever mounted on said support, means actuated by the operation of each key lever to move said sliding support and carry the circuit-closing lever into engagement with the projections on the key lever when the latter moves in one direction, and tripping means to permit the return of said support and said key upon the complete operation of said key lever to prevent the engagement of the teeth with said circuit-closing lever when the key lever moves in the other direction.

In testimony whereof I have hereunto set my hand in presence of two subscribing witnesses.
